DESIGN FOR A BARREL OR SIMILAR CONTAINER

Ross T. Corey, Richmond, Calif.

Application November 26, 1937, Serial No. 73,193

Term of patent 14 years

To all whom it may concern:

Be it known that I, Ross T. Corey, a citizen of the United States, residing at Richmond, in the county of Contra Costa and State of California, have invented a new, original, and ornamental Design for a Barrel or Similar Container, of which the following is a specification, reference being had to the accompanying drawing, forming a part thereof.

Figure 1 is a top plan view of the barrel or similar container.

Figure 2 is a front elevational view thereof.

Figure 3 is a bottom plan view thereof.

Figure 4 is a side elevational view thereof.

Figure 5 is a fragmental vertical sectional view of the container. The plane of section is indicated by the line 5—5 of Figure 2.

Figure 6 is a fragmental horizontal sectional view of the container. The plane of section is indicated by the line 6—6 of Figure 2.

I claim:

The ornamental design for a barrel or similar container substantially as shown.

ROSS T. COREY.
